UNITED STATES PATENT OFFICE

2,263,510

HOUSING STRUCTURE

Harvey B. Lindsay, Evanston, Ill.

Application January 26, 1938, Serial No. 187,056

1 Claim. (Cl. 189—1)

My invention relates to housing structures, in general, but more especially to the general type of housing structures shown in U. S. Letters Patent No. 2,017,629, granted to me October 15, 1935, and involving, generally stated, skeleton framework and plates of sheet metal secured to the framework and extending across openings therein, my present invention relating to the construction of the corner portions of the housing.

The invention has application to a wide range of housing structures including refrigerator structures especially of the transport type, and passenger and freight car bodies.

One of my objects is to provide a housing structure of the general character shown in said patent whereby objectionable protruding parts of the means fastening the sheet metal plates to the framework, are eliminated to the end of improving the appearance of the structure and in addition, in the case of vehicular housing structures, rendering the surface of the structure of "streamline" contour.

Another object is to improve upon the corner construction of structures involving the framework and plate feature referred to, to the end of reducing the number of shapes required for producing the structure with consequent economy of construction; producing a stronger corner construction with a given amount of metal than hitherto possible; permitting of the variation in the shape of the corners within a wide range; and producing, if desired, a construction of "streamline" contour; and other objects as will be manifest from the following description.

Referring to the accompanying drawings:

Figure 1 is a view in side elevation of an end portion of a car body embodying my invention.

Figure 2 is a fragmentary perspective view of one of the similar upper corner portions of the framework of the body of the car.

Figure 3 is a view like Fig. 2 showing the plates and securing means applied to the framework.

Figure 4 is a plan view of one end of a blank from which certain of the plates at junctions of the side walls and roof, are formed.

Figure 5 is a perspective fragmentary view showing the blank formed into its final condition.

Figure 6 is a broken enlarged sectional view taken at the line 6 on Fig. 1 and viewed in the direction of the arrow.

Figure 7 is a section taken at the line 7 on Fig. 6 and viewed in the direction of the arrow.

Figure 8 is a fragmentary enlarged sectional

view taken at the line 8 on Fig. 1 and viewed in the direction of the arrow.

Figure 9 is an enlarged sectional view taken at the line 9 on Fig. 8 and viewed in the direction of the arrow showing the plate-securing bar in separated relation to the structure with which it cooperates; and

Figure 10, a fragmentary view like Fig. 9 illustrating a modification of the flanged edge of the sheet metal plates.

I have chosen to illustrate my invention as incorporated in a railway car body, as for example a refrigerator car, but without any intention of limiting it thereto.

Referring to the particular illustrated construction, the car body is shown as supported on an underframe comprising cross bearers 11 supported on car trucks (not shown) and a surrounding frame formed of channel side sills, one of which is represented at 12, and end sills.

Extending over, and along, the end and side sills are angle irons one of which is shown at 13, with a sheet metal plate hereinafter referred to interposed therebetween, the angle irons and sills being secured together in any suitable way, as for example by bolts or rivets.

Superposing, and secured to, the underframe is a skeleton car-body-forming framewise structure comprising portions of the side walls, end walls, and roof of the car.

This framewise structure which is formed of metal bars of channel shape, with their channels facing outwardly, and having oppositely extending flanges 14 on their free edges, affords at the side walls, end walls, roof, and the vertical corner portions of the car and along the marginal edges of the roof and at the corner portions of the latter, openings to be filled with sheet metal plates spanning them and held in position on the framework by means as hereinafter described.

Some of the bars forming the skeleton framework referred to extend horizontally along the side and end walls of the car adjacent the upper and lower edges of these walls as represented at 15 and 16 and in curved condition at the several vertical corners of the structure as shown of the upper portion of the car at 17, the lower bars 16 being connected with the

angle irons 13 in any suitable way as for example by welding them thereto as represented at 18 and 19. Others 20 and 21 of these bars extend horizontally along the central line of the roof portion of the car and adjacent its lateral edges, respectively, and others 22 crosswise of

the roof adjacent the end walls of the car and at intervals along the roof. Still others 23 of these bars, secured at their lower ends to the bars 16, extend vertically from the bars 16 to the horizontal bars 15 at opposite sides of the vertical corner portions of the structure and also at intervals along the walls; and others shown at 24, of curved contour, from the upper bars 15 and 17 to the corner portions of the roof frame formed of the bars 21 and 22 and 10 also at intervals along the walls.

The various bars forming the skeleton framework referred to are shown as continuous across all points of intersection between bars, the various bars being rigidly secured together to form the framework in any desired way, preferably being braced at the various points of intersection by gusset plates 25, as shown, if the framing is desired to be "knock-down," or by welding for example, if the framing is desired to be permanent.

The framework at the roof portion of the car is shown as reinforced by crosswise disposed Z-bars 26 extending the full width of the roof portion and to which the bars of the roof framework above described are secured.

If desired the several bars may be reinforced at suitable intervals to prevent spreading in the securing thereto of the sheet metal plates, as by providing clips 27 shown as of U-shape applied to straddling position on the bars as represented of the clip in Figs. 8 and 9 where one such clip is shown as applied to one of the vertical channel bars 23, the clips being secured to the bars in any desirable way, as for example by welding them thereto.

The various openings provided by the framework are filled with sheet metal plates the marginal edges of which, inwardly flanged as shown, extend into the channels of the several frame bars referred to in which they are rigidly clamped by clamping bars, preferably of channel shape, engaging the marginal edges of the plates; those portions of the clamping bars which cooperate with the straight frame bars being 45 straight as represented at 28, 29, 30, 31, 32 and 32^a and those portions which cooperate with the curved frame bars being curved as represented at 33, 34 and 35, whereby these clamping bars are caused to nest with the frame bars with which 50 they cooperate.

The clamping bars are held in assembled relation to the framework and plates by any suitable means, as for example screws, rivets or bolts 36 which render the clamping bars and consequently the respective plates individually removable for replacement or substitution in the event they become damaged.

The plate hereinbefore referred to as interposed between the side and end sills of the underframe and the angle irons 13, is represented at 37 this plate forming a floor for the car body with its marginal edges bent upwardly and thence inwardly to form flanges 38 which extend at their extremities into the lower portions of the channels of the frame bars 16 and in which they are clamped in place by the clamping bars co-operating with these frame bars.

The provision of the framework generally as shown contemplates the provision of a car body 70 the vertical corner portions of which between the adjacent pairs of vertical bars 23, and the upper marginal edges of the roof of which between the bars 15 and the bars 21 and 22, are of curved shape in cross section and the corners 75

of the roof margins between the bars 17 and 24 are of segmental spherical shape, whereby the car body is rounded at all of its corners presenting much the same form as that of a basket.

5 These rounded portions of the car body are formed by providing the plates for use at these locations and represented at 39, 40, 41, and 42 at one of the similar four corners of the car body, of the desired contour, the plates which are used at the other openings of the framework being flat, such of the flat plates as are shown being represented at 43, 44 and 45.

The flanges on the sheet metal plates for co-operation with the clamping bars are illustrated at 46, these flanges on the curved edges of the several curved and segmental spherical plates 39, 40, 41 and 42 being formed by slitting the edges of the plates in flat condition as shown at 47 in Fig. 4 and bending the tongues 48 thus provided between the slits to flange forming condition as shown in Fig. 5, the tongues thus edge-wise abutting to form a continuous flange when the plates are deformed into the desired curved condition.

As will be understood from the foregoing the inner edge portions of the clamping bars as they are forced inwardly into the channels in the frame bars and into engagement with the flanges 46 on the sheet metal plates, tend to draw these plates into taut condition and hold them in place.

Except in the case of extremely thin metal plate it is desirable to bend the marginal edges of the plates into flange form preliminary to the application of the clamping bars.

I have found that to produce substantial tension in the plates in clamping them to place it is necessary not only that the plates be preliminarily bent generally as shown either by the full lines at 50 or the dotted lines at 51, to generally conform to the adjacent edge portions of the frame bars over which they extend; but that, unless the sheet is very stiff, the inner edges of the plate flanges 46 should be definitely bent in an inward direction into curved form as for example as shown by full lines at 52 or by the dotted lines at 53 and 54, where very stiff metal is used the bend may approximate that shown at 55 in Fig. 10.

It has been found that the closer the bend 52, 53 or 54 extends to the bottom wall 56 of the frame bar, the less the resulting tension on the plate when finally assembled, and the farther this bend from this bottom wall, the greater the resulting plate tension. Furthermore, that for a given tension in the plate the thinner the sheet the closer the bend 52—54 should conform to the engaging edge of the adjacent leg of the clamping bar, and the heavier the plate the more open this bend should be.

By providing the frame members as of channel form and the clamping bars of similar form, the clamping bars extend substantially flush with the plates producing a streamline surface free of projections which not only makes for a desirable appearance of any structure in which the invention may be embodied, but also lends itself to the streamline effect of vehicle bodies.

The provision of the car body framework as shown and described permits of the forming of the rounded exterior surfaces of any desired radius or curvature, and even of practically square form if desired, the construction being extremely strong particularly as concentration of stresses at the corners of the structure and

which occurs where three corner members meet, is avoided.

Furthermore, by constructing a housing in accordance with my invention, the number of structural shapes required for the entire structure is greatly reduced inasmuch as the only two shapes required are those for the channel frame-bars and the fastening bars resulting in great reduction in heavy rolling mill die costs, as compared with structures as hitherto provided.

No claim is made herein to the feature whereby the sheets or plates are tensioned in the assembling of the parts of the structure, nor to the feature of tensioning the sheets or plates more or less as desired, as these features are claimed, by structure and method claims, in my pending application for United States Letters Patent, Serial No. 214,785, filed June 20, 1938, which was filed as a continuation in part of the present application.

While I have illustrated and described a particular construction embodying my invention I do not wish to be understood as intending to limit it thereto as the same may be variously modified and altered without departing from the spirit of the invention. 25

What I claim as new and desire to secure by Letters Patent is:

In a housing structure: a self-sustaining frame the superstructure thereof formed throughout of channel members of uniform cross section defining flat side and roof surface portions with curved surfaces at certain of the corners of the structure; said members formed as relatively shallow channel members of rolled steel shapes comprising bottom web members, side flange members and outwardly directed margins projecting from said channel flanges; certain of said web members continuous across intersections with meeting flange and margin members mitered at their junctions at said intersections to provide channels continuous across each of said intersections; gusset plates underlying and secured to each of the webs at such intersections; and with curved frame members defining said curved surfaces forming continuations of the flat surface defining members in said side and roof portions.

HARVEY B. LINDSAY.
